(57) **CLAIM**

The ornamental design for a combination control stick/armrest for an aircraft, as shown and described.

DESCRIPTION

FIG. 1 is a rear, left perspective view of a combination control stick/armrest for an aircraft according to my design;

FIG. 2 is a rear elevation view thereof;

FIG. 3 is a left side elevation view thereof;

FIG. 4 is a right side elevation view thereof;

FIG. 5 is a front elevation view thereof; and,

FIG. 6 is a top plan view thereof.

No bottom plan view is included as no features of the claimed design are visible therein.

1 Claim, 6 Drawing Sheets

FIG. 2

FIG. 3

FIG. 4

FIG. 5

FIG. 6
